BENJAMIN H. SHAPIRO, OF BROOKLYN, NEW YORK.

ORNAMENTAL LAMP SHADE AND METHOD OF MAKING SAME.

Application filed May 14, 1928. Serial No. 277,424.

My present invention relates generally to ornamentation and has particular reference to the ornamentation of lamp shades which are made of parchment, paper, or similar fibrous material. From a broader aspect, my invention relates to the ornamentation of sheet material in general, particularly of the character mentioned above and popularly employed for lamp shades and the like.

10 It is one object of my present invention to provide an inexpensive, simple, yet highly effective method of ornamenting sheet material of the character referred to; and thereby to provide ornamented sheet material having a unique and attractive appearance.

Another object of my invention lies in providing a method of ornamentation which is capable of innumerable variations and hence of wide applicability. Although I have here-
20 in illustrated and shall hereinafter describe my invention as applied to the ornamentation of lamp shades, nevertheless it will be understood that as to certain phases of my invention such as specific application is not es-
25 sential.

It is one feature of my invention to make use of the fibrous character of the sheet material designed to be ornamented. More particularly, I contemplate the weakening of
30 the fibrous material along predetermined ornamental lines and in such a manner as to loosen the fibrous texture of the material along such lines.

Another feature of my invention lies in effecting an ornamentation which embodies contrast. Thus, where the ornamental fibrous sheet material is employed in the manufacture of lamp shades, at least one contrasting effect is produced by the passage of
35 light through the relatively unweakened material as a whole and also through the weakened lines of ornamentation.

A particular feature of my invention lies in producing a color contrast effect by the actual employment of only one coloring medium. By the provision of predetermined weakened areas, and the consequent variation of texture, I produce the effect of two colors by subjecting the entire sheet material
45 to a single bath of coloring matter, the latter being absorbed by the fibers of the material and being automatically absorbed by an increased extent along the predetermined lines of loosened or weakened texture.

50 Another feature of my invention lies in combining the features outlined above and

thereby producing a three-fold contrast. Thus, I may employ spaced perforations or severed portions along the predetermined lines of weakness. Such severance serves not only to permit the direct passage of light through such perforations, but it also serves to expose the interior fibers of the material and thereby enhances the effect automatically produced by the uneven penetration of the
60 65 coloring matter into the fibers of the material.

In accordance with my object relating to cheapness and simplicity, it is a feature of my invention to provide the weakened lines of loosened texture by simply striking up integral ridges at intervals from the sheet material. This serves to forcibly bend the fibrous material and to loosen the texture
70 75 thereof in the contemplated manner.

In one embodiment of my invention, I sever the apices of these ridges to provide perforations of the character previously mentioned, and I accomplish this by a unitary operation through the employment of a suitably constructed die or similar instrumentality.

In another embodiment of my invention, weakened linear areas are produced by simply folding or creasing the fibrous material along lines of predetermined ornamentation.

To enhance the effects produced by my method of ornamentation, I prefer to employ sized, glazed, or oiled material, or to initially size or glaze a fibrous material so as to reduce the normal absorptive power thereof.

For the attainment of the foregoing objects and such other objects as may hereinafter appear or be pointed out, I have illustrated my invention in the accompanying drawings in which—

Figure 1 is a perspective view of a lamp shade constructed in accordance with my invention;

Figure 2 is a fragmentary portion on an enlarged scale of the blank of sheet material employed in producing the lamp shade of Figure 1;

Figure 3 is a fragmentary view upon a greatly enlarged scale of the right-hand lower corner of Figure 2; and

Figure 4 is a fragmentary cross-section taken substantially along the line 4—4 of Figure 3.

In the drawings, I have illustrated my invention applied to a lamp shade of known variety and comprising a metal spider or frame 10, to the edge of which a blank of

ornamented parchment or paper 11 is attached in the downwardly divergent manner illustrated. The shade constituted by the blank 11 may be of any configuration or 5 shape. In the illustrated embodiment I have shown a configuration in the nature of a frustum of a cone, and I have shown the lower edge of the shade scalloped as at 12.

My invention contemplates the ornamentation 10 of the shade 11 by the provision thereon of suitably treated lines arranged along ornamental directions and in ornamental combinations to produce, for example, the depiction 13 shown in Figure 1.

15 In Figure 2 I have shown a fragmentary portion of the blank employed in manufacturing the shade of Figure 1. The blank may be of any desired fibrous material such as paper or parchment. It may be sized or 20 unsized, although I have found it preferable in carrying out my invention to employ a material which has been oiled or glazed or in some similar manner treated to reduce the normal absorptive power thereof.

25 In accordance with my invention, the lines defining the ornamentation desired are treated to weaken the material along such lines, more particularly, to loosen the texture of the material. In the illustrated construction I 30 have provided a set of spaced ridges along the contemplated lines of ornamentation, these ridges being integral with the material and struck up from the plane thereof.

The lines 14 of Figure 2 are shown upon a 35 greatly enlarged scale in Figure 3, and the latter figure, when viewed in connection with Figure 4, discloses the nature of the treatment to which the illustrated blank has been subjected.

40 By means of a suitable die or similar instrumentality I provide the spaced ridges 15, these ridges being substantially rectangular in shape in the illustrated embodiment. Obviously, however, they may be provided 45 with circular, oval, or other shapes, depending upon requirements.

In Figure 4, it will be observed that the walls 16 which define these ridges are integral with the sheet material itself. By forcing 50 these walls out of the plane of the sheet material, they are not only attenuated to a slight degree, but the fibrous texture thereof is considerably loosened.

It will also be noted that I have illustrated 55 the ridges 15 with their apices severed, the openings or perforations 17 being thereby reduced at intervals along the lines of ornamentation. This severance may be effected by properly designing and employing the 60 instrumentality or die which produces the ridges.

A severance of the character illustrated 65 results not only in the provision of the perforations which permit light to pass unimpeded therethrough, but it exposes the in-

terior fibers of the material adjacent to such perforations. For example, the extremities 18 of the walls 16 are constituted of exposed and loosened fibers of the material.

After having treated the material so as 70 to weaken predetermined linear areas thereof, I subject the entire material to a liquid coloring matter, either by dipping, spraying, or otherwise. The coloring matter will be absorbed by the fibers of the entire material. 75 If the material is unsized, it will be absorbed to a greater extent than if the material is glazed or sized. In either event, the absorption will be considerably greater along the weakened areas, the loosened fibers having a 80 greater absorptive power than the other fibers of the material. Accordingly, the coloring matter will automatically concentrate along the lines of weakened texture. Where ridges are employed for producing the desired 85 weakness, the coloring matter will concentrate in and around the walls of the ridges and also between the latter.

As a result, the subsequent drying of the 90 material and of the coloring matter will 95 saturate the fibers along the ornamental lines with a relatively concentrated mass of color. The appearance produced will be practically the same as that which would result from deliberately painting, by hand, along the ornamental lines.

In Figure 2, the shaded areas around the 100 spaced ridges represent the areas of concentrated color; and in Figure 3 the darkened 105 areas 19 indicate upon an enlarged scale how these areas arrange themselves along the predetermined and desired ornamental lines. The darkened areas will not be definitely defined but will merge gradually into the relatively lighter color of the body of the material. This serves not only to enhance the unique effect produced but also serves to simulate the effect which would be produced by painting by hand.

In the figures, it will be noted that the areas 110 immediately adjacent to the margins of the blank are similarly of a darker shade. This is due to the fact that the original cutting of the blank to the desired shape weakens the 115 texture adjacent to the peripheral edges of the blank and exposes the interior fibers along these edges.

Where the perforations 17 are provided, the exposed fibers in the ends 18 of the walls 16 will serve further to enhance the absorption 120 by these weakened areas of the coloring matter. As a result, immediately adjacent to the openings or perforations 17 the concentrated areas will be most completely saturated and will appear darkest in hue. A 125 novel and unique effect is in this way produced, because of the contrast between the extremely light openings 17, the very dark boundaries of these openings, the darkened areas 130 19 extending in a vague manner away

from the openings 17, and the relatively lighter shade of the body of the material.

It will be understood that the perforations actually produced need not, and in all probability will not, be as uniform and accurate in shape as illustrated in Figures 3 and 4. In other words, the proper employment of a suitable die will serve to puncture completely through the material in certain cases and to puncture with varying degrees of completeness at other places. In fact, it is preferable for the sake of attractive appearance that the perforations be more or less ununiform and somewhat ragged.

It will also be understood that the weakened linear areas may be produced by means other than the provision of ridges. For example, I have found that in the manufacture of lamp shades wherein the material is provided with a set of pleats, the creases producing the pleats are to a certain extent capable in a similar manner to weaken the texture of the material adjacent to the creases. In such an event, no ridges need be provided, but perforations along the lines of creasing will provide a very attractive appearance.

It will also be obvious that many changes in the details herein described and illustrated for the purpose of explaining the nature of my invention may be made by those skilled in the art without departing from the spirit and scope of the invention as expressed in the appended claims. It is therefore intended that these details be interpreted as illustrative and not in a limiting sense.

Having thus described and illustrated my invention, what I claim as new and desire to secure by Letters Patent is—

1. The method of ornamenting fibrous sheet material, which comprises treating the material along predetermined ornamental lines to loosen the texture of the material along said lines, and subjecting the material to a liquid coloring matter, whereby said coloring matter will automatically concentrate along said lines of loosened texture.

2. The method of ornamenting fibrous sheet material, which comprises treating the material along predetermined ornamental lines to loosen the texture of the material along said lines, and dipping and removing the material into and from a bath of coloring matter, whereby said coloring matter will penetrate the fibres of the material and will automatically concentrate along said lines of loosened texture.

3. The method of ornamenting fibrous sheet material, which comprises sizing the material to reduce its normal absorptive power, treating the material along predetermined ornamental lines to loosen the texture of the material and restore the absorptive power thereof along said lines, and subject-

ing the material to a liquid coloring matter, whereby said coloring matter will automatically concentrate along said lines of loosened texture.

4. The method of ornamenting fibrous sheet material, which comprises sizing the material to reduce its normal absorptive power, treating the material along predetermined ornamental lines to loosen the texture of the material and restore the absorptive power thereof along said lines, and dipping and removing the material into and from a bath of coloring matter, whereby said coloring matter will penetrate the fibres of the material and will automatically concentrate along said lines of loosened texture.

5. The method of ornamenting fibrous sheet material, which comprises perforating the material along predetermined ornamental lines and also loosening the texture of the material around said perforations, and immersing the material in a coloring matter, whereby said coloring matter will penetrate the fibres of the material and particularly through the walls of said perforations, thereby automatically concentrating along and adjacent to said lines.

6. The method of ornamenting fibrous sheet material, which comprises forcing a set of ridges out of the plane of the material and along predetermined ornamental lines, said procedure loosening the texture of the material of said ridges, severing said ridges at their apices to expose the interior fibres of said loosened-texture material, and applying a liquid coloring matter to said ridges, whereby said coloring matter will penetrate said interior fibres and the fibres adjacent thereto and will automatically concentrate around said ridges.

7. The method of making an ornamental lamp shade which comprises cutting a blank of fibrous material to the shape desired, forcing the material of the blank out of the plane thereof along lines of predetermined ornamentation, said procedure being such as to loosen the texture of the material along said lines, immersing the entire blank in a liquid coloring matter whereby the latter will penetrate the fibres of the blank and will automatically concentrate along said lines of loosened texture, and then permitting the blank to dry.

8. The method of making an ornamental lamp shade which comprises cutting a blank of fibrous material to the shape desired, forcing the material of the blank out of the plane thereof at spaced intervals along predetermined ornamental lines, thereby producing a plurality of spaced integral ridges, severing said ridges at their apices to expose the interior fibres thereof, and applying a liquid coloring matter to said ridges, whereby said coloring matter will penetrate the fibres thereof and will concentrate along and adjacent said lines of ornamentation.

9. An ornamental lamp shade comprising a blank of fibrous material, said blank having predetermined linear areas thereof weakened so as to loosen the fibrous texture thereof, and 5 a coloring matter in absorbed association with the fibres of the blank and concentrated throughout the fibres of loosened texture.
10. An ornamental lamp shade comprising a blank of fibrous material, said blank having 10 predetermined linear areas thereof weakened so as to loosen the fibrous texture thereof, and a coloring matter in absorbed association with the fibres of the blank and concentrated throughout the fibres of loosened texture, said 15 weakened linear areas being provided with spaced perforations so as to provide a contrasting effect between the light passing directly through the perforations and the light passing through the adjacent areas of 20 concentrated color.
11. An ornamental lamp shade comprising a blank of fibrous material, said blank having predetermined linear areas thereof weakened so as to loosen the fibrous texture thereof, and 25 a coloring matter in absorbed association with the fibres of the blank and concentrated throughout the fibres of loosened texture, said weakened linear areas being provided with a set of spaced ridges struck 30 up from the blank.
12. An ornamental lamp shade comprising a blank of fibrous material, said blank having predetermined linear areas thereof weaken-

ened so as to loosen the fibrous texture there- 35 of, and a coloring matter in absorbed asso- ciation with the fibres of the blank and con- centrated throughout the fibres of loosened texture, said weakened linear areas being pro- 40 vided with a set of spaced and perforated ridges struck up from the blank.

13. An ornamental lamp shade comprising a blank of fibrous material, said blank having predetermined linear areas thereof weaken- 45 ed so as to loosen the fibrous texture there- of, said areas being produced by forcibly bending the material of the blank out of the plane thereof.

14. An ornamental lamp shade comprising a blank of fibrous material, said blank having predetermined linear areas thereof weaken- 50 ed so as to loosen the fibrous texture there- of, said areas being produced by forcibly striking integral ridges at intervals out of the blank material.

15. An ornamental lamp shade comprising 55 a blank of fibrous material, said blank having predetermined linear areas thereof weaken- ed so as to loosen the fibrous texture there- of, said areas being provided with a set of 60 spaced ridges forcibly struck-up from the plane of the material and having their apices severed to provide perforations.

In witness whereof I have signed this speci- 65 fication this 10 day of May, 1928.

BENJAMIN H. SHAPIRO.
